(57) **CLAIM**

We claim the ornamental design for a bracket for a truck rack, as shown and described.

DESCRIPTION

FIG. 1 is an environmental perspective view of a bracket for a truck rack.

FIG. 2 is an alternate perspective view thereof;

FIG. 3 is a front elevational view thereof;

FIG. 4 is a left side elevational view; (the right side of the design is a mirror image of the left side, and is therefore not shown);

FIG. 5 is a back elevational view thereof;

FIG. 6 is a top plan view thereof; and,

FIG. 7 is a bottom plan view thereof.

The broken line showing of the truck rack is included for the purpose of illustrating environment and forms no part of the claimed design.
